ELECTRIC HORN

Richard C. Nielsen and Peter Nielsen, Omaha,
Nebr., assignors to Jubilee Manufacturing Com-
pany, Omaha, Nebr., a corporation of Nebraska

Application January 3, 1950, Serial No. 136,540

7 Claims. (Cl. 177—7)

1

This invention relates to improvements in electrical sound warning signals.

The primary object of this invention is the provision of an improved electric automobile horn capable of producing a louder and more powerful sound than possible with conventional construction. This is enabled thru the improved use of the two way pull-motor for operating the armature to which the diaphragm is attached.

A further object of this invention is the provision of an electric sound signal utilizing a pair of electromagnets for operating an armature to which the diaphragm is connected; the armature being so constructed and arranged with respect to the electromagnets that the horn may be set in operation and continued in operation without the use of a lag device.

A further object of this invention is the provision of an improved electric automobile horn wherein the diaphragm armature is disposed in such relation to a pair of electromagnets that one of the magnets will attract the horn before the other for the purpose of initially setting the armature into operation upon closing of a circuit.

A further object of this invention is the provision of a loud powerful type of electric warning signal embodying a pair of electromagnets so constructed and arranged as to operate with unequal power upon the armature, whereby without the use of a lag device the horn may be initially set into operation.

Other objects and advantages of the invention will appear in the following detailed description.

In the accompanying drawings, forming a part of this specification, and wherein similar reference characters designate corresponding parts throughout the several views,

Figure 1 is a transverse cross sectional view taken thru portions of the automobile horn, showing the arrangement of the parts thereof.

Figure 2 is a plan view of the horn.

Figures 3 and 4 are fragmentary cross sectional views taken substantially on the respective lines 3—3 and 4—4 shown in Figure 1 of the drawings.

Figure 5 is a diagrammatic view showing the horn circuit system.

In the drawings wherein for the purpose of illustration is shown only a preferred embodiment of the invention, the letter A may generally designate the electric warning signal or horn. It includes a casing or frame structure B; electromagnetic assemblage C; diaphragm and armature assemblage D and circuit maker and breaker means E.

Referring to the supporting or frame struc-

ture B, the same includes a disc-shaped base plate 10 to which the lower ends of adjusting supporting bolts 11, 12 and 13 are connected in right angled relation. The upper ends of the supporting standards or bolts 11, 12 and 13 are screw threaded and receive thereover a sub-base plate or frame member 14, provided with apertures for freely receiving therethru the screw threaded ends of the standards. Nuts 15 are provided on each of the screw threaded ends of the standards 11, 12 and 13 for adjusting the position of the sub-base plate 14 with respect to the base plate 10, and also, as will hereinafter appear, to adjust the spacing of the electromagnetic coils with respect to each other and the armature.

The facing surfaces of the plates 10 and 14 are adapted to support upper and lower electromagnets 23 and 24 respectively of the assemblage C. Each of these electromagnets includes a sleeve-like core 25; a coil 26 and a field pole piece 27. The cores 25 are provided with aligning passageways 29 therethru. The remote ends of the cores are inserted thru suitable openings in the base plates 10 and 11 and peened thereover as at 30. The parts of each of the cores 23 and 24 as thus provided, are so constructed and arranged so that the electromagnets are respectively securely attached to the plates 10 and 14, as clearly shown in Figure 4. There is an air gap between 35 the facing pole pieces of the electromagnets, designated by the letter X, shown in Figure 4.

The armature arrangement for the electromagnets preferably consists of an armature shaft 40 having an armature 41 of disc-shaped formation secured therewith intermediate the ends thereof and disposed in the air gap X. The ends of the shaft 40 extend freely thru the passageways 29 of the two electromagnets. The lower end of the shaft 40 is screw threaded and mounted centrally upon the diaphragm D and adjustably secured thereto as by a nut 42. The upper end of the shaft 40 is likewise screw threaded and extended thru suitable apertures in a spring arm 45, shown in Figure 1. This screw threaded end 40 of the shaft 40 receives a nut 46 whereby the position of the armature and its mounting on the spring arm 45 may be adjusted, for the purpose of properly spacing the armature disc 41 in the air gap X, in accordance with the principles of this invention to be hereinafter discussed.

Referring to the circuit maker and breaker assemblage E, the lower electromagnet 24 is provided with a contact point 50 mounted upon a metal spring arm 51. The spring arm 51 is 55 mounted in insulated relation upon a rim of the

sub-base plate 14, as shown in Figure 1, by means of bolts 53 which also secure the remote end of the spring arm 45 above mentioned. The arm 45 is provided with an opening therethrough for freely receiving the contact point or tip 50, as shown in Figure 1. The arms 45 and 51 are insulated from each other by an insulation strip 52.

The breaker point assemblage for the lower magnet furthermore includes an adjustable contact member 56 mounted upon a rigid arm piece 57, which is also secured in position by the bolts 53. Normally, the contact points or tips 50 and 56 are in engagement. The plane of their engagement may be adjusted not only by means of the bolt 46, but also by the nut 58 which is adjusted upon the screw threaded end 59 of the point 56.

The coil 26 of the lower magnet 24 has a wire 60 extending for connection at 61 to an extended end of the spring arm 51, as shown in Figure 2. The contact point 56 is grounded to the frame of the horn, as shown at 65 in Figure 5.

The coil of the upper electromagnet 23 has a wire 70 extending for connection at 71 to a lateral portion 72 of a metallic spring arm 72^a, shown in Figure 1. The arm 72^a has a contact point 73 mounted thereon. The upper coil breaker point assembly is mounted as by bolts 74 upon the sub-base plate 14, as shown in Figure 1, and the steel spring arm 72^a is insulated from the frame by an insulation strip 75, shown in Figure 1, which contacts a portion 76 mounted upon and in conducting relation with the armature shaft, as shown in Figure 1. The spring arm 72^a normally is urged downwards against the portion 76 and urges the contact point 73 downward and into engagement with a contact point 77. The latter is mounted upon a conductor cross bar 78. Bar 78 is bolted at 79, as shown in Figure 3, upon the frame sub-plate 14 at one end and at its opposite end it is provided with an adjusting bolt 80 having a head assemblage which includes a lock nut, and a screw threaded end 81 which screws into a portion of the sub-plate 14. With this arrangement the bar 78 may be lifted and lowered to adjust the relative position of the contact points 73 and 77.

It is to be noted that the contact point 73 is insulated with respect to the frame of the horn and the contact 77 is grounded to the frame, as diagrammatically indicated at 81 in Figure 5.

For the coils of the electromagnets 23 and 24, arc quenching resistors 90 and 91 are bridged across the respective contact points or tips of the two breaker point assemblies, as shown in Figure 5.

A battery or outer source of current 95 is grounded at 96. A main switch 97 is provided, and a horn sounding button 98, all in the circuit. The wires of the two coils remote from their connections with the breaker point assemblies are connected to a battery terminal connecting bolt 99, best shown in Figure 4.

Thru the adjustable bolt mountings of the armature shaft 40 upon the diaphragm and the spring arm member 45, the position of the armature disc 41 may be adjusted in the air gap X. Thus it may be spaced a distance Y, constituting an air gap between the same and the lower electromagnet 24, and the distance Z, constituting an air gap between the same and the upper electromagnet 23. This off center location of the armature disc 41 is intended to be sufficient (assuming that both electromagnets are of equal

strength), that the closer magnet will initially attract the armature to set it in oscillation.

It is furthermore to be noted from Figure 5, that the coil of the lower electromagnet may be wound to produce greater strength for attraction of the armature. The differential in strength between the two magnets is also intended to be sufficient (by itself) to enable the lower electromagnet to initially attract the armature and set it into oscillation, even tho the armature may be positioned in the center of the air gap X.

The optimum arrangement, however, is shown in the drawings where not only is the armature 41 closer to the pole of the electromagnet 24, but also the latter is stronger. This insures that the lower electromagnet will initially attract the armature to set the same into vibration.

The diaphragm D is provided with a cover 100, riveted or otherwise secured at 101 to the base plate 10.

It is acknowledged that heretofore it was old to provide two electromagnets for actuating the armature of an electric sound signal. However, the lagging and other devices heretofore provided for insuring the initial starting of the horn, add to the expense thereof, and prevent compactness of the assemblage, because of the necessity of using a larger number of parts with less space for installation. The present horn does not necessitate a lag device. In it both breaker point assemblies are initially closed, and both electromagnets are simultaneously energized upon pushing the horn button 98, resulting in closure of the main operating switch. However, in view of the above, the armature will be set in oscillation and the breaker assemblages alternately opened and closed as long as the button 98 closes the circuit, for the vibration of the diaphragm and sounding of the horn.

Various changes in the shape, size and arrangement of parts may be made to the form of invention herein shown and described, without departing from the spirit of the invention or the scope of the following claims.

We claim:

1. In an electric sounding signal the combination of a pair of relatively spaced mounting plates having means to detachably mount the same in spaced relation for adjustment towards and away from each other, a pair of electromagnets mounted in fixed relation upon the facing surfaces of said plates, one upon each plate, said electromagnets including cores with aligning passageways and individual windings, the electromagnets being relatively spaced to provide a definite air gap therebetween, a diaphragm mounted upon one of said plates, an armature including an armature shaft having ends extending thru the passageways of the electromagnets, the shaft being connected to the diaphragm with the armature in the air gap between the electromagnets, means connecting the armature shaft yieldably to said frame in position so that the armature may be adjusted in the air gap with respect to said electromagnets, individual circuit making and breaking assemblies for said electromagnets associated and arranged with respect to the armature for alternate opening and closing upon oscillation of the armature.

2. In an electric sounding signal the combination of a pair of relatively spaced mounting plates having means to detachably mount the same in spaced relation for adjustment towards and away from each other, a pair of electromagnets mounted in fixed relation upon the facing surfaces of

said plates, one upon each plate, said electromagnets including cores with aligning passageways and individual windings, the electromagnets being relatively spaced to provide a definite air gap therebetween, a diaphragm mounted upon one of said plates, an armature including an armature shaft having ends extending thru the passageways of the electromagnets, the shaft being connected to the diaphragm with the armature in the air gap between the electromagnets, means connecting the armature shaft yieldably to said frame in position so that the armature may be adjusted in the air gap with respect to said electromagnets, individual circuit making and breaking assemblies for said electromagnets associated and arranged with respect to the armature for alternate opening and closing upon oscillation of the armature, the armature being positioned eccentrically in the air gap so that there is a smaller effective gap between the same and one of the electromagnets than with respect to the other electromagnet.

3. In an electric sounding signal the combination of a pair of relatively spaced mounting plates having means to detachably mount the same in spaced relation for adjustment towards and away from each other, a pair of electromagnets mounted in fixed relation upon the facing surfaces of said plates, one upon each plate, said electromagnets including cores with aligning passageways and individual windings, the electromagnets being relatively spaced to provide a definite air gap therebetween, a diaphragm mounted upon one of said plates, an armature including an armature shaft having ends extending thru the passageways of the electromagnets, the shaft being connected to the diaphragm with the armature in the air gap between the electromagnets, means connecting the armature shaft yieldably to said frame in position so that the armature may be adjusted in the air gap with respect to said electromagnets, individual circuit making and breaking assemblies for said electromagnets associated and arranged with respect to the armature for alternate opening and closing upon oscillation of the armature, the armature being positioned eccentrically in the air gap so that there is a smaller effective gap between the same and one of the electromagnets than with respect to the other electromagnet, and one of said electromagnets having a greater effective electromagnetic strength than the other magnet.

4. In an electric sounding signal the combination of a pair of relatively spaced mounting plates having means to detachably mount the same in spaced relation for adjustment towards and away from each other, a pair of electromagnets mounted in fixed relation upon the facing surfaces of said plates, one upon each plate, said electromagnets including cores with aligning passageways and individual windings, the electromagnets being relatively spaced to provide a definite air gap therebetween, a diaphragm mounted upon one of said plates, an armature including an armature shaft having ends extending thru the passageways of the electromagnets, the shaft being connected to the diaphragm with the armature in the air gap between the electromagnets, means connecting the armature shaft yieldably to said frame in position so that the armature may be adjusted in the air gap with respect to said electromagnets, individual circuit making and breaking assemblies for said electromagnets associated and arranged with respect to the armature

mature for alternate opening and closing upon oscillation of the armature, the electromagnets each including a winding, one of which windings is of such nature as to produce a greater electromagnetic strength in that electromagnet than the other whereby upon closing of a circuit wherein the electromagnets are disposed, the electromagnet of greater strength will initially attract the armature.

5. In an electrical sounding signal the combination of a frame structure, a pair of relatively spaced electromagnets mounted upon said frame structure and having an air gap therebetween, an armature common to both of said electromagnets disposed in the air gap between the electromagnets and in spaced gap providing relation with respect to each of the electromagnets, a diaphragm connected with the armature for vibration upon oscillation of the armature, one of said electromagnets being of greater electromagnetic strength than the other for initially attracting the armature upon closing of an electromagnetic circuit, a normally closed circuit maker and breaker for each of said electromagnets having means associated and arranged with respect to the electromagnets that the circuit makers and breakers will be alternately operated to opened position, and a circuit for the electromagnets having the circuit makers and breakers operatively connected therein.

6. In an electric sounding signal the combination of a frame structure, a pair of relatively spaced electromagnets mounted upon said frame structure and having an air gap therebetween, an armature common to both of said electromagnets disposed in the air gap therebetween and in spaced gap providing relation with respect to said electromagnets, a diaphragm mounted upon the frame structure and having connection with said armature for vibration upon oscillation of the armature, a normally closed circuit maker and breaker for each of said electromagnets, a circuit for the electromagnets having the circuit makers and breakers operatively associated therein for alternately energizing said electromagnets, means to alternately open said normally closed circuit makers and breakers upon closing of said circuit, one of said electromagnets having means to give it a greater electromagnetic strength for initially attracting the armature upon the closing of the circuit, and gap adjusting means connected with said armature and frame structure and normally holding the armature in position with the smaller air gap between the same and the stronger electromagnet to aid in the initial attraction of the armature by said stronger electromagnet.

7. As an article of manufacture an electric sounding signal comprising a frame structure, a pair of relatively spaced electromagnets mounted upon said frame structure and having an air gap therebetween, a normally closed circuit maker and breaker for each of said electromagnets mounted upon the frame structure and in circuit with the respective electromagnets for controlling flow of current therethru, a diaphragm connected with said frame structure, means connecting the armature with the central portion of said diaphragm, and means mounted upon said frame structure and connected with the armature at the opposite side of the armature from the diaphragm for adjusting the position of the armature in the air gap between said electromagnets, said means being so adjusted as

to hold the armature closer to one of the electromagnets than the other during deenergizing periods of said electromagnets whereby the electromagnet with the smaller air gap between it and the armature will initially attract the armature upon closing of a circuit thru said electromagnets.
